UNITED STATES PATENT OFFICE

GEORGE ARTHUR PHILLIPS, OF MIDDLE PARK, VICTORIA, AUSTRALIA

DOCUMENT FILING DEVICE

Application filed October 2, 1929, Serial No. 396,622, and in Australia October 11, 1928.

One object of this invention is to so improve loose leaf books, files, and the like wherein sheets are assembled on pillars, that access to any sheet will be facilitated, and 5 such sheet can be positioned flatly to allow it to be easily written on, or its contents easily read, without the user having to hold either that sheet or the sheet facing it, or having to make temporary adjustments, such 10 as varying the length of pillars.

Another object is to so improve document files that the pillars can be mounted in any of several positions on a tray or similar base.

A further object is to apply hinge devices 15 to pillar files to enable a user to vary beneficially the position of the documents as the files are opened, as compared with their position when the files are closed. In known 20 files pillars extending downwardly coact with others extending upwardly, each passing through a slot or perforation in the papers, and a top cover plate from which pillars extend downwardly is retained against displacement by a spring clip fixed to a base; 25 but in that arrangement the sheets are tightly gripped at their margins so that marginal and adjacent parts cannot conveniently be inspected by a user when he opens the file, as the sheets do not naturally lie flat and wide 30 apart, but have to be held apart, usually by hand, during inspections and the making of entries. I provide each file with a fitting which allows the filed sheets to be widely 35 opened so that they lie flatly—bookwise, and naturally stay so without being held.

My fitting has hinged members which include lower plates or leaves, integral with or attached to a base,—such as a tray, drawer bottom, or part of a file cover; and has an 40 upper plate or leaf carrying pillars normally rising about vertically or at right-angles over the base—but said pillars can be swung outwardly so that the papers on file can be located more conveniently for reference; 45 then the pillars will be approximately horizontal instead of vertical, and the position of the back edges of the papers will also be changed similarly.

50 Hinges are not necessarily fixtures—as

when desirable they include separable elements so that the base can be detached.

I illustrate—diagrammatically—in the drawings herewith, in which the scales differ,—embodiments of my invention; details will vary according to the type of file or holder to which the invention is applied.

Figure 1 is a perspective sectional view of part of a tray carrying a file of papers or sheets.

Figure 2 shows, in end elevation, part of Figure 1, but with the sheets opened bookwise, so that the pillars have taken new positions.

Figure 3 shows part of Figure 2 in perspective with sheets and upper hinge parts swung over to illustrate details at the hinge base.

Figure 4 shows in perspective—without sheets—a file as in Figure 1, with—instead of a tray—a cover of book form, parts only of which are shown.

Figure 5 is a perspective view of a tray, three sides of which are fitted with lower elements of hinges to allow a user to attach at any side a pillar-carrying file member which is fitted with upper elements of hinges.

Figure 6 is a perspective view of file parts having relatively numerous pillars.

In these drawings, A is a base, such as a tray, drawer bottom or cover underpart, to which is attached—as by rivets—lower hinge elements B, to which an upper hinge element, shown as a leaf B¹, is jointed as at B². File pillars C project upward from leaf B¹, in the case of Figures 1, 4 and 6, and may be of any suitable type, that is continuous or in sections, and straight or curved, the pillars illustrated being straight. D is an upper binding plate which carries downwardly extending pillars D¹ bearing against the plate B¹; and the pillars C and D¹ may form pairs—see Figure 6.

The pillars retain the assembled sheets E, and the file may have protective covers E¹—Figure 1—and plate D may be retained against displacement by, for example, a spring clip F, one end thereof being attached to the leaf B¹ as shown in Figure 3.

As shown by Figure 4, the file may have

a cover of book form, that is having connected to base A, a back A² carrying an upper cover A³.

As shown by Figure 5 assembled sheets can be attached to one or other of the edges of the base A, by reason of the presence of a plurality of hinge lower elements B, at different edges of the base.

Sockets B² on these elements can be engaged by upper hinge elements, shown as pins B⁴, of the leaf B¹. I provide means to prevent accidental separation of the hinge elements when in connected position. Thus I provide a pin B⁵ against which edge B⁶ abuts when in closed position.

As seen in Figure 1, hinge leaf B¹ is horizontal or superposed on leaf B when the file is closed, but when the file is swung fully open, leaf B¹ moves in an arc into a new position shown by Figures 2 and 3 without any shifting of base A; and in the Figure 2 position, which is characteristic of my construction, there are material advantages,—leaf B¹ then extending upwards and the pillars extending outwards.

I claim:—

1. In loose sheet holders, a base, sheet-filing devices, and hinged means of connection of the devices with the base, comprising hinge sockets on the base and hinge pins carried by the filing devices, whereby the latter swing in an arc away from the base to re-position the sheets as in opening a book, the said pins being disconnectible from and reconnectible to said sockets, the sockets being located at a plurality of edges of said base to enable location of the filing devices at any of said edges.

2. In loose sheet holders, a base, sheet-filing devices, and hinged means of connection of the devices with the base, comprising hinge sockets on the base and hinge pins carried by the filing devices, whereby the latter swing in an arc away from the base to re-position the sheets as in opening a book, the said pins being disconnectible from and reconnectible to said sockets, the sockets being located at a plurality of edges of said base to enable location of the filing devices at any of said edges, the pins being slidable relatively to the sockets.

3. A file to hold assembled sheets, having a base carrying a plurality of sets of hinge sockets and filing devices having separate sets of pillars for sheet assembly and hinge parts adapted to slidably engage any selected set of sockets, and means to prevent accidental displacement of said filing devices when the file parts are assembled.

4. In witness whereof I have hereunto signed my name to this specification at Melbourne in the State of Victoria, in Australia, this fifth day of September, 1929.

GEORGE ARTHUR PHILLIPS.
